FLEXIBLY MOUNTED MIRROR

Knud Sorensen, Hempstead, N. Y.

Application December 4, 1952, Serial No. 22,544

Term of patent 7 years

(Cl. D33—9)

To all whom it may concern:

Be it known that I, Knud Sorensen, a citizen of Denmark, residing at Hempstead, Long Island, in the county of Nassau and State of New York, have invented a new, original, and ornamental Design for a Flexibly Mounted Mirror, of which the following is a specification, reference being had to the accompanying drawing, forming a part hereof.

Fig. 1 is a perspective view of a flexibly mounted mirror showing my new design;

Fig. 2 is a side view in folded position; and

Fig. 3 is a front elevational view of the mirror element thereof.

The dominant features of my design reside in the portions shown in full lines.

I claim:

The ornamental design for a flexibly mounted mirror, substantially as shown and described.
